UNITED STATES PATENT OFFICE.

CHARLES STAFF, OF ROYAL OAK, MICHIGAN.

CARBURIZING MATERIAL.

1,131,801.

Specification of Letters Patent. Patented Mar. 16, 1915.

No Drawing.

Application filed February 11, 1913. Serial No. 747,687.

To all whom it may concern:

Be it known that I, CHARLES STAFF, a citizen of the United States of America, residing at Royal Oak, in the county of Oakland and State of Michigan, have invented 5 certain new and useful Improvements in Carburizing Material, of which the following is a specification, reference being had therein to the accompanying drawings.

10 The invention relates to the art known as cementation in which iron or steel is carburized by treatment with a suitable carburizing agent under high temperature.

In the present state of the art various substances have been employed as carburizing agents—such, for instance, as bone black, and other animal and vegetable carbons. Many of these materials, while efficient as carburizers have other detrimental properties, such as shrinkage under heat, loss of efficiency upon successive uses, or high cost, which prohibits their commercial use.

It is the object of the present invention to obtain a carburizing material which is free 25 from these objections, and to this end the invention consists, first, in the treatment of the iron or steel with a material having newly-discovered advantageous properties; and further in the specific material employed for this purpose.

My new carburizing agent is formed from a substance known as vegetable ivory, the botanical name of which is phytelephas macrocarpa. I have discovered that this 35 material which is of an unusually dense

hard nature will carburize with very slight shrinkage, and that it also contains chemical constituents which render it efficient as a carburizing agent. This substance is used for the manufacture of buttons and other 4 similar articles and the chips or cuttings forming the waste of this industry may be used for forming the carburizing material. The carburizing process may be carried out by packing the iron or steel directly in the 45 chips or cuttings, but I preferably subject the material to a pre-heating sufficient to carbonize it before it is employed as a carburizing agent. The carburizing is then carried out in the same manner as where 50 other materials are used.

While I have described the specific material as vegetable ivory, it is obvious that there may be other substances of a similar nature which may be employed as substitutes. The essential qualities are, first, the absence of shrinkage upon heating, and second, a chemical composition rendering it efficient as a carburizer.

What I claim as my invention is: 60

A carburizing material for metals comprising a carbonized substance known in its natural state as vegetable ivory.

In testimony whereof I affix my signature in presence of two witnesses.

CHARLES STAFF.

Witnesses:

JAMES P. BARRY,
HENRI E. BOWMAN.
